US00D977971S

(12) **United States Design Patent** (10) Patent No.: **US D977,971 S**
(45) Date of Patent: **** Feb. 14, 2023**

(54) **ECOLOGY CAN END**

- (71) Applicant: **Stolle Machinery Company, LLC**, Centennial, CO (US)
- (72) Inventors: **Dennis Cornelius Stammen**, Brookville, OH (US); **Robert Joseph Will**, Maria Stein, OH (US); **Christopher Lawrence Macke**, Sidney, OH (US); **Patrick Kevin McCarty**, Dayton, OH (US); **Robert Herbert Brussell**, New Bremen, OH (US); **Greg Scott Williams**, Wapakoneta, OH (US); **Steven Todd Albright**, Covington, OH (US)
- (73) Assignee: **Stolle Machinery Company, LLC**, Centennial, CO (US)
- (**) Term: **15 Years**
- (21) Appl. No.: **29/839,991**
- (22) Filed: **May 25, 2022**

Related U.S. Application Data

- (63) Continuation of application No. 29/734,200, filed on May 11, 2020.
- (51) LOC (14) Cl. **09-07**
- (52) U.S. Cl. USPC **D9/438**
